ATTORNEYS

UNITED STATES PATENT OFFICE.

ERNEST BOYD, OF NEW YORK, N. Y.

HOSIERY.

Application filed August 9, 1921. Serial No. 490,882.

To all whom it may concern:

Be it known that I, ERNEST BOYD, a citizen of the United States of America, and resident of New York, in the county of Bronx and State of New York, have invented certain new and useful Improvements in Hosiery, of which the following is a specification.

This invention relates to the art of wearing apparel and particularly to stockings, socks and similar garments which are made of knitted material.

In the art, to which my invention particularly relates, it has long been common to make hose or stockings of knitted material such as silk, cotton and wool and to knit the same in flat or tubular web, and it has also been common to fashion the flat web as well as the tube into a simulation of the shape of the leg and foot. It is well known that when stockings and other garments, made of knitted material and especially of knitted material composed wholly of one thread, become torn, or cut, or are snagged in any way, as by the finger nails in drawing on the stocking, or by any other means, the tear or snag will cause the giving away of the inter-chain of loops for an indefinite distance, this being familiarly known as "running," and, when this condition occurs, it is practically impossible to stop it or overcome it and it eventually causes unsightly appearance, ruins the stocking, and causes wastage of expensive materials. This is also true with reference to the heel and toe of such stockings, which, when they become worn or cut through by abrasion, it is difficult to darn so as to stop the running, resulting in the entire foot giving away along wide and long stretches, eventually reaching the leg of the stocking and running indefinitely. This results in discarding both stockings of the pair, even though one of the pair is not injured in any particular. It is well understood also that stockings of very light material, such as those made of silk and lace, are not strong or durable in the foot portions and especially at the toe and heel, the bottom of the foot portion being distinguished from the top of the foot portion in order to illustrate the fact that, when the bottom of the foot wears, cuts, or runs, for any cause whatever, the entire stocking and usually the pair are discarded, thus making even a relatively cheap pair of stockings quite expensive.

By the employment of my invention, all the foregoing difficulties, objections and deficiencies are overcome and completely removed, and I am enabled to produce not only a very slightly, but a very strong, durable and economical stocking, which can be worn indefinitely and, in consequence, is exceedingly cheap.

In carrying out my invention, some of the objects thereof may be stated as follows: to provide, as an article of manufacture, a stocking blank comprising the entire leg portion and the top of the foot portion, the same being knitted so that the two general parts are integral or formed in continuity one with the other, and so finished along the edges as to enable them to be readily seamed or stitched and trimmed or cut, if desired, without raveling or causing the wales of the material to "run"; to provide, as an article of manufacture, a stocking blank having the foot and leg portions formed in continuity and the edges of the foot portion provided with a selvage, and the said blank formed of either flat or tubular knit material fashioned so as to have the general form of the leg and the top of the foot; to provide a stocking composed in leg and top of the foot of one kind of material, and in the bottom and heel of the foot of another kind of material, the latter being not only in contrast with the leg and top of the foot, but of a denser, or more closely knitted fabric or material, which will stand the wear and usage and friction without cutting or running, and the two parts being seamed or joined together by a flat, soft seam which will not be objectionable to the user; to provide a stocking wherein the heel and bottom portion of the foot are made double or of double thick material, which, additionally, is of a different kind of knitted material from that of the top of the foot and the leg; to provide a reversible stocking wherein the heel and bottom portion or sole are of either single or double thick material, and which is so seamed to the top of the foot and leg of the stocking as to present the same appearance both inside and outside, and which heel and bottom of the foot portion may be applied to the other portions of the stocking with a double, covered seam; to provide a

stocking wherein the leg and top portion of the foot are very elastic transversely and relatively inelastic longitudinally, and wherein the bottom and heel of the foot are 5 made of contrasting material of denser fiber and, in consequence, much stronger and more durable, which material is quite elastic transversely, but substantially inelastic longitudinally; to provide a stocking which, in 10 the leg and upper portion of the foot may be made of very expensive material, while the bottom and heel of the stocking may be made of comparatively inexpensive material, which can be readily renewed in case the 15 bottom or heel of the stocking becomes worn or cut, or runs during wear; to provide a stocking wherein the leg portion is made of one material and the top or "cuff" is formed of a different and contrasting material 20 which is stronger, more durable and will not "run" when cut, snagged or torn, and which cuff may be seamed to the leg of the stocking by a double, covered seam showing the same on both sides so that the stocking may 25 be reversible as heretofore explained; and to provide as an article of manufacture a seam for sewed articles, applicable to and adapted for different portions of a garment such as between the leg and top or cuff of 30 the stocking and the top of the foot and bottom and heel of the foot of the stocking; and to provide a method by which a stocking and a seam for sewed articles, as set forth in the foregoing, may be produced 35 quickly, economically and with great facility.

With the foregoing objects in view and others which will be detailed during the course of this description, my invention consists in the parts, features, elements and combinations thereof and in the art, process or method hereinafter described and claimed.

In order that my invention may be clearly understood, I have provided drawings 45 wherein:

Figure 1 is a view showing in side elevation a stocking in full length embodying my invention and illustrating the contrasting 50 materials of which the different parts of the stocking are formed and also showing the lines of seams;

Figure 2 is a plan view showing my article of manufacture consisting of the leg 55 and the top part of the foot of a stocking, embodying my invention;

Figure 3 is a plan view showing the blank from which the bottom and heel of the foot 60 of the stocking of Figure 1 is formed;

Figure 4 is a vertical sectional view of a portion of a stocking showing the mode of attaching the top or cuff to the leg;

Figure 5 is a cross-sectional view illustrating the seam for sewed articles and also 65 the double foot of the stocking, the view be-

ing particularly intended to show the mode of disposing the several parts of the foot of the stocking so as to illustrate the method of producing the double, covered seam; and

Figure 6 is a view similar to Figure 5 70 showing a different position of parts and the manner of manipulating the latter to place them in the final position for use.

For brevity and a clear understanding of the article and method of making the same, of my invention, I will refer to the parts of my stocking, as follows: the body of the stocking from the beginning of the heel-seam,—which may also be the beginning of the leg-seam,—up to the double top, as the leg 1; the top of the foot portion, as the foot-top 2; the bottom of the foot portion, as the foot-bottom 3; the heel portion of the foot-bottom, as the heel 4; and the double top, as the cuff 5.

Referring to the drawings, and particularly to Figure 1, the leg 1 of the stocking, such as usually worn by women, is made either from a flat blank or from tubular knit material, and in either instance is either 90

fashioned to the proper shape during the knitting, or is shaped subsequently and seamed as required. The foot-top 2 is knitted integral with the leg 1, and, if the latter is fashioned either in the flat or in the 95 tube, the foot-top will also be fashioned. If, however, the leg is cut to shape, the foot-top likewise will be cut to the desired shape and size.

In any event, it is to be understood that my invention comprises the leg and 100 foot-top made integral and formed in continuity, these two parts being an article of manufacture and sold as such in the market. In the process of knitting the leg, either in the flat web or tubular web, the leg may be 105

narrowed and properly fashioned in well known manner, and the fashioning and narrowing extended to the foot-top, as clearly shown in Figures 1 and 2. Hence, the leg 110 and foot are made as a continuous operation from the same thread or threads and are of

substantially uniform texture throughout. The leg 1, if made in the flat blank, will be formed with a selvage 6 along both edges, and said selvage edges will be secured together in any suitable way, as by a looping or so-called turning-off machine, which makes a seam 7 which is practically invisible. If the leg is tubular knit, there will 115 be no seam along the back of the leg. The

selvage 6 is continued on opposite sides of the vertex of the angle 8 in the back of the leg, said selvage being indicated by 9, and is also continued around the edge of the 120 foot-top, as indicated at 10. Thus formed, there is no possibility of the article fraying or becoming distorted, the selvages tending to hold the shape of the article and in great measure preventing the edges from curling.

The leg of the article may or may not be 130

provided with a separate cuff 5. If the so as to, in both instances, produce a flat cuff is integral with the leg, which is formed seam; or the seam may be such as is illustrated by merely knitting the leg a little longer and in Figures 5 and 6, or in Figure 4. turning over a portion at the top thereof to 5 for the cuff of the stocking, in which latter event the foot-bottom will be of single 70 thickness.

5 form the cuff, the edge of the cuff is sewed to the leg in any usual manner, as by a looping or turning-off machine, this being done with great facility owing to the manner of impaling the loops of the cooperating 10 portions and stitching the said portions together in a manner to practically hide the seam or line of connection. As shown in Figures 1 and 4, the cuff 5 is made separately from the leg and applied to the latter by a 15 covered seam, the material of the cuff being much more closely knit or of denser fiber, and, consequently, being stronger and more durable. The knitted material from which the cuff 5 is made is known as "Tricot" and 20 "Milanese". This material is so made, and its characteristics are such, that it is not as elastic as the leg, and is more elastic laterally or transversely to the length of the wales than in the direction of the length of 25 the wales. As shown in Figure 4, the material of the cuff 5 is folded double and its two edges are turned in or hemmed, as at 11, and between the said two hemmed edges, the upper edge 12 of the leg is inserted, and the three edges stitched together, as at 13, the line of stitching and seam being covered by the cuff. This is accomplished by turning the cuff wrong side out, the edges at the back of the stocking 30 being left separated and the stitching being accomplished while the parts are in this position. Then the cuff is reversed and drawn into the position shown in Figure 4, whereupon the edges at the back of the leg are 35 stitched together in any suitable way.

As shown in Figures 1 and 2, the foot-top is provided around its entire edge with the selvage 10 which will prevent raveling and form an edge, to which the foot section can 40 be stitched without destroying the texture or causing the material to "run", the said selvage being extended, as at 9, up the back of the leg to the vertex 8 of the angle.

The foot-bottom 3 and the heel 4 are made 45 of contrasting material much more dense of fiber and either cut or fashioned as shown in Figure 3, which illustrates the blank of the foot-bottom and heel in plan, the numeral 14 indicating the fold-line, in the sole of the 50 foot-bottom, which extends along the center thereof lengthwise. When the blank is folded on the line 14, the edges 15 will be seamed together so as to produce the point 16 which enters the vertex 8 of the angle 55 in the back of the leg where the selvages 9 join. The opposite edges 17 of the foot-bottom are then stitched to the cooperating selvage edge 10 of the foot-top, and this may be done on a turning-off machine or by an 60 over-edge machine with the edges abutted 65

70 The foot-bottom 3, the heel 4, and the cuff 5 of the stocking, as previously stated, are of contrasting material, much more dense in fiber and stronger and more durable. In 75 selecting tricot and milanese, which are similar and have substantially identical characteristics, I have discovered attributes thereof which adapt them peculiarly to the uses herein set forth. That is to say, I 80 have taken advantage of the fact that, when cut or trimmed, the said material will not run or fray or distort, which characteristics particularly adapt the said material to employment as the foot-bottom, heel and 85 cuff of stockings, since these portions of the stockings are invariably, in use and in handling, subjected to strain and distortion tending to snap the threads. Also, in wear, both the toe and heel of the stocking are subjected 90 to constant and vigorous abrasion having a tendency to wear holes therein which, however, will not destroy the material, nor cause it to run; and which, on the other hand, may be darned and sewed, as may be 95 required. Also, as is well known, when the clasp of a garter or garment supporter is applied to the opposite sides of the cuff of the stocking, the material of the latter is 100 very much distorted and in use is placed under very severe strain which tends to cause the clamps or clasps of the garters and supporters to cut or gradually wear through the cuff material. This, however, does not 105 destroy the cuff, nor cause it to run, owing to the peculiar characteristics of the said material and its density and durable qualities. The cuff, wherever cut or worn, may likewise be either darned or sewed, which is an impossibility with the leg of the stocking, as ordinarily constructed of one thread, 110 knitted material. Another characteristic of tricot and milanese is that, while it is a little more elastic transversely of the wales than longitudinally thereof, it as a whole 115 is inelastic as compared with the leg and foot-top. This characteristic renders the material particularly suitable for the foot of stockings, since it will not become unduly distorted and can be made to size, and the 120 size maintained throughout entire use of the stockings. The value, of the foregoing characteristics and features, will be readily appreciated when it is understood: (1) that the leg 1 and foot-top 2 are more 125 elastic transversely than longitudinally, enabling the stocking to readily fit snugly many different sizes of legs without stretching lengthwise inordinately; (2) that, while the foot-bottom, compared with the foot- 130

top, has little elasticity, it nevertheless will stretch sufficiently transversely,—or in the directions of the double arrow *a*,—of the wales of the material, and have very little stretch longitudinally of the foot-bottom, or at a right-angle to the arrow *a*, this enables the foot-bottom of a given size to maintain approximately that size lengthwise, which is the desideratum, since, if the foot-bottom stretches inordinately lengthwise, it will fold over at heel or toe and hurt the foot, while transversely or in the direction of the arrow *a*, the foot-bottom may stretch sufficiently to fit a flat foot or feet of varying thickness; and (3) that, due to the form of the blank of Figure 3, the heel 4 will have greater stretch vertically, or in the direction of the double arrow *b*, than at a right-angle to said arrow, this being because at this portion the wales of the material run approximately transversely of the leg, thus preventing the heel from stretching in a direction substantially at a right-angle to the arrow *b*, which would be substantially in the direction of the greater elasticity of the leg and foot, and at the same time enables the heel to stretch vertically, or in the direction of the arrow *b*, which is substantially at a right-angle to the greater elasticity of the leg, hence, the heel will not stretch in the direction of the length of the foot and be unduly elongated, but will, in drawing on the stocking, yield vertically to prevent the leg and heel from being torn apart. These are valuable features in stockings of any grade or value and, particularly, in stockings of high grade and value, since they lend durability and life to the article, as well as comfort during wear.

If the bottom of the foot of the stocking is made of a single piece or single thick material, it may be applied to the foot-top by a single seam, a hem being turned in the material of the foot-bottom, and the said hemmed portion being applied to the selvage 10 of the foot-top by a line of stitching which will not show on the outside of the stocking. This sort of seam is soft, and, inasmuch as it is not along the portion of the foot which bears the weight of the body, cannot hurt the foot and is not objectionable. The foot-top and foot-bottom may, however, be united by a flat seam, as on a turning-off or other suitable machine.

If the foot-bottom is made of double thick material, the seam will be a double seam such as shown in Figures 5 and 6, wherein it will be seen that the two plies 3 and 3^a of the foot-bottom are laid upon the single ply of the foot-top 2, and the three plies are sewed together by a line of stitching 18. When thus stitched together, the inner ply 3^a of the foot-bottom is drawn outwardly and then the stocking is turned inside out, thus causing the outer ply 3 of

the foot-bottom to follow the contour of the inner ply, the foot-top of the stocking extending above the said two plies. Thus a double, covered seam 18 is produced which cannot hurt the foot and is not objectionable. This seam, in both its forms, is peculiarly adapted for stockings, and the parts thereof described, and, as such, constitutes, according, to my invention, a seam for sewed articles, and I desire it understood that, while I have shown this seam applied to, and believe that it is peculiarly adaptable for, stockings in the places described, I do not wish to be limited to this use of the seam or particular application thereof.

A stocking made as shown, with a double foot, is reversible, inasmuch as the line of stitching around the foot is covered on both sides and presents exactly the same appearance both inside and out. Hence, it makes no difference which way the stocking is worn, and when by abrasion or long wear, one ply of the foot-bottom is cut or worn, the stocking can be reversed, so as to present to the outside of the stocking that ply of the foot-bottom which is unworn and probably good as new. Reversing the stocking has no effect at all upon the cuff, when applied as described in the foregoing, since the seam presents the same appearance both inside and outside of the leg.

It will be understood that, according to my invention, I have produced an article of manufacture made according to the method outlined, which has its vital portions reinforced, said vital portions being the foot-bottom, heel and cuff, the same being subjected to greatest wear; and it will be understood that the denser or more durable material, of which the foot-bottom and heel of the stocking are made, may be extended over the top of the toe of the stocking so as to give to that portion of the stocking greater durability and longer wear. As shown in Figures 1 and 2, the heel is extended quite a distance up the leg and gradually narrows to the vertex 8, this being for the purpose of extending the heel beyond the top of the highest low quarters, pumps, or sandals worn by women, thus preventing the heel from being worn, torn or ripped by the constant compression of the heel of the shoe against the heel of the stocking.

The dot and dash line 19 in Figure 2 indicates the fold-line of the foot-top, and the corresponding line of the foot-bottom is indicated at 14, in Figure 3. The two foot parts, when folded along the lines 14 and 19, will take the form shown in Figure 1; and it will be seen that the sole portion of the foot-bottom is seamless from the toe-point 20 back to the point 21, which is the beginning of the heel seam 15, produced by joining the two edges 15 of Figure 3. On the other hand, the foot-top is seamless and the fold 19

extends the whole length of the front of the leg, as seen in Figure 1. The seams 7, 10 and 15, regardless of how made or formed will be soft and flat and are so located that 5 they can neither hurt, annoy, nor be uncomfortable to the wearer. I desire to lay stress upon the contrasting material of the leg and foot-top as compared with the foot-bottom and heel; also upon the durability of 10 the foot-bottom and heel as compared with the leg and foot-top; also upon the reversibility, detachability and interchangeability of the foot-bottom.

In order that my claims may be understood, I desire to call attention to the following. 15 There are two types of knitted goods, one formed with a chain stitch which is so constituted that the breaking of a thread will cause that thread to "run" as it is called. 20 The other form is so constituted that when a thread is cut it will not run because of the fact that the constituent elements are so interlocked as to inhibit running. Of the latter class are goods known in the trade as 25 tricot or milanese or as glove silk fabric. There is also that large class of woven fabrics which are so interlocked as to inhibit the threads from running.

Having thus described my invention, what 30 I claim and desire to secure by Letters Patent is:

1. A stocking comprising the leg and top of the foot portion knitted in one piece to conform in size and shape to a predetermined 35 leg and foot combined with a foot portion adapted to complete the stocking, the latter being cut from a knitted material having the characteristic that its component parts are so locked as to inhibit running, with 40 means to secure together the corresponding edges of said parts.

2. A stocking comprising the leg and top of the foot portion, said top of the foot portion extending to the toe, said parts knitted in 45 one piece to conform in size and shape to a predetermined leg and foot, combined with a foot portion adapted to complete the stocking, the latter being cut from a knitted material having the characteristic that its com-

ponent parts are so locked as to inhibit running with means to secure together the corresponding edges of said parts. 50

3. A stocking comprising the leg and top of the foot portion knitted in one piece to conform to the leg and foot and provided with a selvage along the edge thereof, in combination with a foot portion adapted to complete the stocking the latter being cut from a knitted material having the characteristic that its component parts are so 55 locked as to inhibit running with means to secure together corresponding edges to complete the stocking. 60

4. The method of making a stocking with a double foot bottom and heel section cut 65 from piece goods of a kind that will not run as described which consists in superimposing on either side of the top of the foot section of a knitted stocking one of said foot bottom and heel sections so that their edges coincide, 70 then stitching said three layers together along their edges, then inverting one of said layers so as to remove it from the other two and then turning the stocking inside out so as to superimpose another of said layers on 75 said inverted layer, thus forming a double foot bottom and heel portion and a single top of the foot portion.

5. A stocking wherein the leg and top of the foot portion is knitted to conform to a 80 predetermined size and shape and the remaining foot section is formed from tricot, said parts being suitably secured together.

6. A stocking with a foot portion the top section whereof is knitted in one piece as a 85 continuation of the leg portion and the bottom section thereof is formed of a double thickness of knitted piece goods material having the characteristic that its component parts are so locked as to prevent running, 90 said two sections being secured together by a common seam.

Signed by me at New York city, N. Y., this 5th day of August, 1921.

ERNEST BOYD.
